UNITED STATES PATENT OFFICE.

EDNA L. SMITH, OF HENO, OHIO.

DESIGN FOR AN UMBRELLA-COVER.

SPECIFICATION forming part of Design No. 36,092, dated September 30, 1902.

Application filed August 13, 1902. Serial No. 119,582. Term of patent 3½ years.

To all whom it may concern:

Be it known that I, EDNA L. SMITH, a citizen of the United States, residing at Heno, in the county of Butler and State of Ohio, have produced a new, original, and ornamental Design for Umbrella-Covers, of which the following is a specification.

This invention relates to a new and ornamental design for an umbrella-cover, and the essential features reside in the design illustrated in the accompanying facsimile drawing, which represents a plan view of the cover.

The design is characterized by a circular body 1, having a central circular blue field 2, with a white star 3 concentrically arranged therein. Surrounding the field 2 in regular concentric relation toward the perimeter of

the body are a series of alternate white and red stripes 4 and 5 of circular form, and at the edge of the body is a wider marginal blue stripe 6, also of circular form and completely surrounding the white, and within the stripe 6 are a plurality of regularly-arranged circularly-aligned white stars 7.

Having thus described the invention, what is claimed as new is—

The ornamental design for an umbrella-cover, as herein shown and described.

In testimony whereof I affix my signature in presence of two witnesses.

EDNA L. SMITH.
